HANGING FIRE WALL AND METHOD OF CONSTRUCTING SAME

John J. O'Brien, New York, N. Y.

Application July 8, 1949, Serial No. 103,565

29 Claims. (Cl. 61—48)

This invention relates to piers and to means and methods for isolation and control of fires which may occur thereunder and more particularly to concrete fire wall, or bulkheads under piers, though in some of the claims the invention is not limited to piers or concrete walls.

One object of the invention is to provide an improved wall of this kind which may be installed without submarine equipment and which may be constructed in situ of concrete under the pier.

Another object of the invention is to provide an efficient fire wall hanging under the pier and extending from the pier deck to below the water line.

Other objects are to provide a fire wall of this kind which will be rugged and durable, and will withstand shocks if the pier is struck by heavy boats.

Other objects of the invention are to increase the flexibility of the fire wall while maintaining its functions and above advantages, and to this end to provide a fire wall of independently swinging sections flexibly connected in a manner to prevent the passage of fire through the connections.

Another object of the invention is to provide a fire-stopping barrier where the fire wall joins the pier deck.

Other objects are to provide improved methods of constructing the fire wall to effect the above objects.

Additional objects of the invention are to effect simplicity and efficiency in such walls and methods and to provide an extremely simple wall of this kind which is rugged and durable in use, and economical to construct and maintain.

Still other objects of the invention will appear as the description proceeds; and while herein details of the invention are described in the specification and some of the claims, the invention as described in the broader claims is not limited to these, and many and various changes may be made without departing from the scope of the broader claims.

The inventive features for the accomplishment of these and other objects are shown herein in connection with an improved fire wall or fireproof bulkhead and method of making the same, the wall being made as a single wall or as a number of wall sections flexibly joined and hanging across the space under the pier and extending below the water.

In constructing the wall section or wall under a pier, beams are placed on the pier stringers. The method includes suspending from said beams downwardly extending rods supporting a lower beam above the water line, and securing along the lower beam spaced parallel upright forms between which bolts, rods or cables are passed from said upper beam and secured to the lower beam; and concrete or other plastic material is poured between the forms on the lower beam to form a lower part of a fire wall section.

Then all parts of the lower beam and wall section are simultaneously lowered. The process of building up the form and the pouring are repeated until the wall section is below the water line and has been built up substantially

2

to the stringers, after which the rods, bolts or cables are secured to the upper beam after which the forms are removed to allow the rods, bolts or cables to support the wall.

5 In the accompanying drawing showing, by way of example, several of many possible embodiments of the invention,

Fig. 1 is a fragmental vertical sectional view, partly in elevation, showing one form of a complete wall section and a wall section in course of erection, the section being taken through the pier deck substantially on the line 1—1 of Fig. 3, looking in the direction of the arrows of said line;

15 Fig. 2 is a fragmental horizontal sectional view taken substantially on the line 2—2 of Fig. 1, and showing one form of wall anchoring means, diagonal braces 15 being removed for clearness;

Fig. 3 is a fragmental side elevation of a portion of a pier, a wall section being shown in end elevation;

Fig. 4 is a fragmental longitudinal vertical sectional view, partly in elevation, drawn on a larger scale, showing the upper part of a fire wall with part between the pier stringers;

Fig. 5 is a section taken substantially on the line 5—5 of Fig. 4, looking in the direction of the arrows of said line;

Fig. 6 is a fragmental transverse vertical sectional view, taken substantially on the line 6—6 of Fig. 1, showing the lower part of a wall section during construction;

Fig. 7 is a plan of a yoke piece used during construction;

Figs. 8 to 10 are fragmental horizontal sectional views showing three forms of flexible joint between the sections;

Fig. 11 is a side elevation showing another form of fire wall;

Fig. 12 is an edge or end elevation of the wall of Fig. 11.

40 Figs. 13, 14 and 15 are respectively fragmental side elevation, horizontal section and end elevation showing another form of anchoring means; and

Fig. 16 is a vertical sectional view showing means for suspending the fire wall from a concrete pier deck.

45 In Figs. 1 to 3 are shown a complete fire wall section 10 and an incomplete section 11 beneath a pier 12 carried on transverse bents or rows of piles 13 having cross braces 14 and diagonal swing braces 15 secured thereto. Caps 16 on the respective bents or rows of piles support spaced stringers 17 disposed across and connecting the caps one to another. The pier deck comprises transverse deck planks 19 across the stringers and pier and diagonal floor or deck planks 20 or a concrete floor across the deck planks; or the entire deck floor may be of concrete, but herein a plank deck is described.

50 To erect the fire wall under a plank deck, two deck planks and the floor planks above them are removed to leave a transverse opening 21 above the stringers near a bent or row of piles with proper clearance from the piles. 60 Longitudinally slidable upwardly open upper channel beams 22 are placed in alignment with each other on the stringers in said opening substantially across the pier. These upper beams have short longitudinal slots 23 (Figs. 4 and 5) in the web at intervals and have flanges 24 nearly as high as the top of the deck lower planks.

65 Across the channel beam at intervals are disposed, during construction, flat upper yoke pieces 25 having openings at each side of the beam in which are placed long threaded rods 27 on which are placed nuts 28 engaging the yoke piece, the rods initially extending much above the yoke piece and initially extending down to

near the water level at high tide, and are provided with lower end eyes 29 (Fig. 6) which support lower flat yoke pieces 30 each having at the ends downwardly outwardly turned hooks 31 engaging in said eyes. Across said lower yoke pieces 30 are placed a temporary wooden beam 32 or other suitable beam to provide a temporary foundation for the fire wall, on which beam are nailed studding or small strips 31a of right angular cross section along the top edges of the wooden beam. Upright plywood boards 32a are nailed to the inner face of the studding to provide forms for molding the concrete or other plastic when poured to form the fire wall. Between and against the form is laid on said wooden beam an upwardly open lower channel beam 35 having cross pins 36 passing through the flanges at intervals corresponding to said slots 23 of the upper beam. Bolts or cables 37 are initially passed through said slots 23 and secured at their lower ends to said cross pins 36. If cables are used they are drawn taut. Bolts will remain upright because of their stiffness.

Between the outer ends of the forms where the free end of the fire wall is to be, there is secured an inwardly vertically dove-tailed upright end piece 38 (Fig. 2) of oak or other material to form a protective end edge or fender for the wall; and between the inner ends of the form where the inner end of a wall section is to be, there is secured an upright end piece having a deep inner vertical tongue to form a deep groove 39 (Fig. 8) in the concrete to cooperate with a similar groove 39 of an adjacent wall section 11 to form a space to receive a fireproof vertical spline 40 of suitable fireproof material. Wires 41 (Fig. 6) are passed through the forms to tie the forms together to prevent their spreading apart when the concrete is poured.

Escutcheon plates 42 having horizontally elongated openings 43 therethrough are secured at opposite locations on the inner face of the forms adjacent to a pile to receive and hold a core 43' of horizontally elongated cross-section placed in the openings of the plates across the space between the forms to provide holes 43a through the wall for a purpose to be explained.

The concrete or other plastic material is poured between the forms while the bolts 37 are upright or said cables are taut to form a lower part of a fire wall section after which the nuts 28 supporting the section are simultaneously turned to lower the rods, lower beam and wall section to a new lower position for building up the forms and end pieces and repeating the pouring and process until the wall section is below the water line at low tide and has been built up substantially to the bottom of the stringers or the upper channel beams 22 as will be explained.

The wall section may be built up solidly to the upper channel beam 22; or when the wall section is built up to the bottom of the stringers 17 there may be placed on the wall fireproof horizontal parting plates 45 (Fig. 4) across and along the top of the wall section just at or under the lower plane of the stringers. Then the forms and concrete wall section are built up between the stringers substantially to the upper beam 22, a short tubular form 46 having been placed on the plate around the bolts or cables 37 between the stringers, whereby are formed concrete lugs 47 having vertical openings therethrough, the lugs occupying the space between the stringers substantially to said upper beam 22.

The object of the parting plate 45 is to provide a smooth break between the lug 47 and the wall section if the pier should be struck and heavily jarred by a boat. If the parting plate be omitted a rough break might result, but would do no real harm.

An eye bolt 49 having upper and lower eyes 50 and 51 has its upper eye 50 placed on a pin 52 passing through each pair of aligned openings in the flanges of the upper beam. The upper end of the bolt or the cable 37 is secured to the lower eye 51 of the eye bolts; after the

wall is set the forms, cores, temporary beam, yokes 30 and long bolts 27 are removed to allow the bolts or cables 37 to support the wall section.

The operation is repeated to form the other end section of the wall, and one or more intermediate sections having slightly spaced vertical end edges having adjacent cooperating deep grooves 39, into which grooves are placed a spline plank 40 of fireproof material to form a flexible yieldable fireproof joint.

An eye bolt 54 (Fig. 2) is loosely passed through the escutcheons 42 and openings 43 and 43a and has an eye 55 adjacent to a pile and a head or nut 56 at the opposite end. A pair of straps 57 at opposite sides of the pile are secured by bolts 58, 59 passing through the ends of the straps, one of the bolts 59 passing through the eye for loosely anchoring the wall to the pile.

The object of having the channel beam 22 slideable, and of having the bolt loose in the escutcheon openings 43, is to allow some relative movement between the pier 20 and the beam 22 and between the fire wall and the piles and pier when the pier is struck and jarred laterally, thus to avoid excessive shock to the cables or bolts 37 and the fire wall section.

If desired the wall section 10c may be made thinner 25 between the joints, as shown in Fig. 10, thus requiring less concrete between the joints.

Instead of the joints being made as in Figs. 8 and 10 the concrete wall 10b may be cast in undercut grooves 60 (Fig. 9) of loosely tongued and grooved pieces 61, 62 30 of aluminum or other metal or material.

Instead of erecting the walls as above described, the wall may be prefabricated and transported to the pier and attached to the upper beam 22 by means of the eye bolts 49 and pins 52 as shown.

The form of the invention of Figs. 11 to 15 comprises a fire resisting wall or wall section 10a of concrete suspended from upwardly open aligned shallow upper channel beams 22a secured across adjacent stringers 17 having flanges less high than the adjacent planks 19 and 40 as wide as the space between adjacent planks 19. Short planks 19a are aligned between adjacent beams. Pending bolts or rods 37a passing through bolt holes in the web of the channel beams and having nuts 63 on the upper end engaging the web for holding the bolts, support the 45 permanently installed lower beam 35a as will be explained. A concrete filling 64 between and flush with said adjacent planks 19 covers the beams and nuts.

Cross pins 36a passing through eyes 37b at the lower ends of the rods 37a support U-shaped straps 65 having 50 holes in the upper ends of their arms received on said pins 36a. The lower beam 35a received in said straps supports the concrete or other cast plastic fire wall 10a resting on said lower beam and extending upwardly to the stringers 17, upper beams 22a and short planks 19a.

An upright end piece 38a of oak or other material to form a protective end edge or fender for the wall and having countersunk holes therethrough is held in place by barbed studs 66 in said holes and cast in the wall and having heads 67 in countersinks 68 in said piece.

Means for preventing lateral swinging of the walls but allowing endwise movement relative to the adjacent pile is shown in Figs. 13 to 15 and comprises a horizontal channel iron 70 having a vertical web 71 disposed against adjacent piles 13 of the same pylon, and having a horizontal slot 72 in its mid-part. U-straps 73 disposed around adjacent piles 13 are bolted to the web by bolts 74. A non-traveling slide plate 75 welded fast on the flanges of said channel iron is provided with a horizontal slot 76 65 registering with the slot 72 of the channel iron, said 70 slots receiving a threaded bolt 77 transversely slidably disposed in said slots and having one end welded or riveted to an anchor plate 78 cast mid-way between the wide faces of the wall.

Horizontally movable slide plates 79, 80 having central 75 openings received on said bolt 77 are welded to the bolt

and slidable on said non-traveling plate and the channel iron to allow horizontal relative movement between the piles and the wall parallel to said faces and parallel to the wall as when the pier is jarred laterally. A reinforcement of expanded metal 31 is cast in the main plane of the wall to strengthen the wall.

The walls or wall sections of Figs. 11 to 15 may be constructed by using the rods 27 substantially as those of Figs. 1 to 3; but the temporary beam 32 need not be employed, as the yoke piece 38 may be placed directly beneath the lower beam 35a, and the forms 32a (as in Fig. 6) may be rested directly on the beams 35a.

If the pier deck 19c (Fig. 16) is made of concrete it may be provided with cut-out recesses 82 in its top face and bolt holes 83 from the mid-part of the recesses passing down through the deck; and receiving plates 84 on the bottom of said recesses have countersunk holes receiving pending rods or bolts 37c in said holes 83 and having heads 85 disposed flush in the countersinks and covered by a concrete filling 86 in the recess flush with the top of the deck and covering said heads and plates.

Where wooden decks are used a part of the planking could be cut away or omitted and have a concrete portion substituted, the concrete wall being built up to said portion.

If desired, the plate 78 could be omitted and an eye formed on the tie bolt 77 and disposed on one of the bolts 37a for anchoring the tie bolt.

In general any of the features of any of the species herein may be used with the features of the other species if suitable and desired.

This application is a continuation in part of my abandoned application Serial No. 9,536, filed February 19, 1948.

The invention claimed is:

1. In combination, with a pier deck, pending flexible connectors connected at intervals to the pier deck and hanging under the pier deck; a wall of hardened plastic material secured to said connectors close to said pier deck, and having its lower part disposed a short distance below the water line.

2. In combination, with a pier deck having spaced stringers, a longitudinally slidable beam disposed transverse to the pier deck on the stringers; a vertical wall of hardened plastic material suspended from said beam.

3. In combination, with a pier deck subject to shocks and jars, pending cables beneath the pier deck secured at intervals thereto; a beam secured to the lower ends of the cables below the later line; a masonry wall enclosing said cables and rising from said lower beam substantially to the deck.

4. In combination with a pier deck having spaced stringers, longitudinally slidable aligned upper beams disposed transverse to the pier deck on the stringers; pending eye bolts secured at intervals to the upper beam and having lower eyes; pending cables secured to said eyes; a lower beam secured to the lower ends of the cables; and a wall of hardened plastic material rising vertically from said lower beam and enclosing said cable and rising substantially to said stringers.

5. Fire retarding means for a pier deck having spaced stringers supporting the pier deck; said means comprising a longitudinally slidable upwardly open aligned upper channel beam adapted to be disposed substantially across the pier deck on the stringers and having longitudinal slots in the web and transverse aligned openings in the flanges at the slots; transverse pins in said openings; eye bolts passing through said slots and each having lower eyes, the upper eyes being received on said transverse pins respectively; a pending cable secured to each lower eye; a lower beam secured to the lower ends of the cables; a wall of hardened plastic material rising vertically from said lower beam and enclosing said cables and rising substantially to said channel beam and provided with upper vertical openings enclosing the lower part of the bolts.

6. In combination with a pier deck having spaced stringers, longitudinally slidable aligned upper beams disposed transverse to the pier on the stringers; and a plurality of aligned vertical wall sections of hardened plastic material suspended from said beams and having loose tongue and groove connection with each other.

7. In combination with a pier, a fire wall comprising a plurality of aligned vertical wall sections of hardened plastic material flexibly swingingly suspended beneath said pier and extending below the water; adjacent edges of the sections having secured thereto vertical cooperating tongue-and-groove edge piece having inner under cut grooves in which said material is cast, the edge pieces forming a fireproof flexible joint.

8. In combination with a pier on piles, a swinging wall beneath the pier secured to the pier and having an opening therethrough near a pile; escutcheons in the face of the wall around the opening; an eye bolt passing loosely through the escutcheon and core openings and having an eye adjacent to the pile and a head at the opposite end; a pair of straps at opposite sides of the pile; bolts passing through the ends of the straps, one of the bolts passing through the eye for loosely anchoring the wall to the pile.

9. Fire retarding means for a pier deck having spaced stringers, said means comprising an upper beam adapted to be disposed transversely on the stringers; pending cables secured at intervals to the upper beam between the stringers; a lower beam secured to the lower ends of the cables; a wall of hardened plastic material on said lower beam and enclosing said cable and rising substantially to said upper beam and to substantially fill the space between the stringers at the wall to form a lug, said lug having a vertical hole therein in which the cable is disposed.

10. In combination with a pier having spaced stringers, a beam disposed across the stringers; pending cables secured at intervals to the upper beam between stringers; a lower beam secured to the lower ends of the cables; a wall of hardened plastic material rising vertically from said lower beam and enclosing said cable and rising substantially to said stringers and to said beam between the stringers to form lugs, and a parting board across the wall just under the lugs.

11. In combination with a pier having spaced stringers supporting the pier deck, an upwardly open upper channel beam disposed across the stringers and having longitudinal slots in the web and transverse aligned openings in the flanges at the slots; transverse pins in said openings; eye bolts passing through said slots and having lower eyes, and upper eyes received on said transverse pins; a pending cable secured to each lower eye; a lower beam secured to the lower ends of the cables; a wall of hardened plastic material on said lower beam and enclosing said cables and rising substantially to the stringers and between the stringers and substantially to said upper beam to form large lugs between the stringers and having a horizontal parting plate disposed entirely across and along the wall under the space between the stringers substantially.

12. A method for erecting a wall beneath a structure above water, said method comprising suspending from the structure downwardly extending members supporting a beam above the water line; securing cables taut between the beam and structure; building the lower part of a wall, on said beam, enclosing the cables simultaneously lowering all parts of the beam and wall part; repeating the method until the lower part of the wall is below the water line and has been built up to the final height; securing the cables to said structure; and removing said members.

13. A method for erecting a fire resisting wall beneath a

pier having spaced stringers, said method comprising placing an upper beam across the pier stringers; suspending from the upper beam a horizontal temporary beam; securing spaced upright forms along the temporary beam; laying a lower beam along the temporary beam between the forms; passing cables from said upper beam and securing them to said lower beam; pouring plastic material between the forms to form a lower part of a fire wall section while maintaining said cables taut; then simultaneously lowering all parts of the beam and wall section; building up the form and repeating the pouring and method until the wall is below the water line and has been built up between the stringers and around the cables substantially to the top level of the stringers; securing the cables to the upper beam; and removing the forms and temporary beam to allow the cables to support the wall.

14. A method for erecting a fire resisting wall beneath a pier having spaced transverse stringers thereon; said method comprising placing across the stringers longitudinally slideable upwardly open alined upper channel beams having longitudinal slots in the web; transverse alined openings in the flanges above each slot carrying pins carrying eye bolts having lower eyes; suspending from the channel beam downwardly extending rods supporting a temporary beam above the water line under the pier; securing upright forms along the edges of the beam; laying on said beam an upwardly open lower channel beam having cross pins passing through the flanges; passing cables through said lower eyes, drawing the cables taut and securing them; pouring plastic material between the forms to form a lower part of a fire wall section while maintaining said cables taut; simultaneously lowering all parts of the beam and wall section; building up the form and repeating the pouring and method until the wall section is below the water line and has been built up substantially to the stringers; laying a horizontal parting plate across and along the top of the wall adjacent to the lower plane of the stringers; placing a tubular form around the eye bolt and the cables on said plate; building up the wall between the stringers and around the tubular form substantially to said upper beam; securing the cables to the lower eye of the eye bolts; removing the upright forms and temporary beam to allow the cables to support the wall.

15. In combination with a pier having spaced stringers, an upper beam disposed transverse to the pier on the stringers; pending eye bolts secured at intervals to the upper beam; long bolts suspended from the eye bolts; a lower beam secured to the lower ends of the long bolts; and a wall rising vertically from said lower beam and enclosing said bolts and rising substantially to said stringers and said upper beam.

16. A method for erecting a fire resisting wall beneath a pier having spaced stringers, said method comprising placing a slotted upper beam across the pier stringers; suspending from the upper beam a horizontal temporary beam; securing spaced upright forms along the temporary beam between the forms; passing bolts downwardly through the slots of said upper beam and securing them to said lower beam; pouring plastic material between the forms to form a lower part of a fire wall section while maintaining said bolts midway between the forms; then simultaneously lowering all parts of the beam and wall section; building up the form and repeating the pouring and method until the wall is below the water line and has been built up between the stringers and around the bolts substantially to the top level of the stringers and securing the bolts to the upper beam; and removing the forms and temporary beam to allow the bolts to support the wall.

17. A fire resisting fire wall or curtain of concrete secured beneath a pier comprising spaced stringers disposed on the pier; transverse planks across the stringers, upwardly open alined shallow upper channel beams disposed

across adjacent stringers and having holes in the web at intervals and having flanges nearly as high as the top of the planks and filling the space between adjacent planks; pending rods passing through said holes having nuts on the upper end and engaging the web for holding the bolts, said bolts having eyes at the lower end; a lower beam secured to said eyes; and a wall of hardened plastic material rising from said beam to said stringers and upper beam.

18. In combination, pending rods adapted to be secured beneath a deck at intervals; a beam secured to the lower ends of the rods below the water line; a concrete wall enclosing said rods and rising from said lower beam substantially to near the upper ends of the rods; an upright end piece of oak disposed against an edge face of the wall to form a protective end edge or fender for the wall and having countersunk holes therethrough; and headed studs in said holes and secured in the concrete wall to hold the piece to the wall and having heads in said countersink.

19. Fire retarding means for a pier comprising transverse pylons and a deck thereon; said means comprising a concrete fire wall suspended from the deck adjacent a pylon; a horizontal bar member adapted to be disposed against adjacent piles of the same pylon and having a horizontal slot in its mid-part; straps disposed around said adjacent piles secured to the bar; a bolt transverse slidably disposed in said slot and having one end anchored substantially mid-way between the main faces of the wall section; traveling slide plates having central openings received fast on said bolt and slideable on said bar member.

20. In combination, a fire resisting concrete wall suspended adjacent to transverse pylons beneath a pier deck; a horizontal channel iron having a vertical web disposed with its web against adjacent piles of the same pylon, the web having a horizontal slot in its mid-part; U-straps disposed around said adjacent piles and bolted to the web; a non-traveling slide plate welded fast on the flanges of said channel iron and having a horizontal slot registering with the slot of the channel iron; a bolt transverse slidably disposed in said slots and having one end cast mid-way between the faces of the wall; traveling slide plates having central openings received on said bolt, the plates being welded to the bolt and slideable on said non-traveling plate and the channel iron; and an anchor plate cast mid-way in the wall section parallel to said faces and secured fast to said end of the bolt.

21. In combination, a pier having a concrete deck having a transverse series of cut-out recesses in its top face and vertical bolt holes extending from the mid-part of the recesses through the deck; plates in said recesses having counter holes; pending rods in said holes having heads flush in the countersinks; a concrete filling in the recess flush with the top of the deck and covering said heads and plates; a beam secured to the lower ends of the rods below the water line; a masonry wall enclosing said rods and rising from said lower beam substantially to the deck.

22. In combination, a pier deck; a vertical masonry wall disposed transversely under said pier and extending upwardly to the deck and downwardly just below the water level and spaced from the ground; and means supporting the wall from said pier deck only and allowing longitudinal movement of the wall transversely of the pier deck when the pier deck is jarred laterally, thereby to avoid excessive shock and excessive disintegration and deterioration of the wall.

23. In combination, a pier comprising a deck; a vertical wall disposed under said deck swingingly supported at its upper part only from the deck and adapted to swing slightly allowing longitudinal movement of the wall transversely of the pier, when the pier is jarred laterally, thereby to avoid excessive shock and excessive disintegration and deterioration of the wall.

24. In combination, a pier comprising a deck and transverse pylons supporting the deck; a vertical masonry wall suspended from said deck near and spaced from one of the said pylons and adapted to allow replacement of the pylons

without touching the wall and to allow movement transverse of the pier relative to the lower part of the adjacent pylon; and means for detachably loosely anchoring said wall to adjacent piles for holding the wall from excessive swinging from the pylon and allowing movement of the wall transversely of the pier relative to the adjacent pylon, when the pier is jarred laterally, thereby to avoid excessive shock and excessive disintegration and deterioration of the wall.

25. In combination, a pier comprising a deck and transverse pylons supporting the deck; a vertical wall of reinforced concrete transversely disposed under said deck near one of said pylons and loosely connected to the upper part only to said deck and adapted to move with movement transversely of the pier relative to the deck and the adjacent pylon; said wall extending upwardly to the deck and downwardly just below the water level; and means loosely anchoring the lower part of said wall only to adjacent piles for holding the wall from excessive swinging from the pylon and allowing movement of the wall transversely of pier relative to the pylon, when the pier is jarred laterally, thereby to avoid excessive shock and excessive disintegration and deterioration of the wall.

26. A method for erecting a wall beneath a pier deck above water, said method comprising supporting a horizontal beam above the water line; securing rods to said beam and the deck; building the lower part of a wall on said beam around the rods; lowering the beam and wall part; repeating the method until the lower part of the wall is below the water line spaced from the ground and has been built up to the deck; and suspending the wall from the deck by means of said rods.

27. A method for erecting a fire resisting wall beneath the deck of a pier, said method comprising disposing beneath the deck a horizontal beam above the water line under the pier; passing rods through said deck and securing them to said lower beam; securing spaced parallel upright forms along the beams; pouring plastic material between the forms around the rods to form a lower part of a fire wall section; then simultaneously lowering said forms, beam and wall section; building up the forms and repeating the pouring and method until the wall section is below the water line and has been built up substantially to the deck; securing the rods to the deck; and removing the forms and finally temporary beam to allow the rods to support the wall.

28. A method for erecting a fire resisting wall beneath the deck of a pier having transverse pylons; said method comprising placing across the pier structure longitudinally slideable upper beams; suspending from the beam pairs of downwardly extending rods disposed near a pylon and

- 5 temporary structure above the water line under the pier; laying a horizontal lower beam on said structure; securing spaced parallel upright forms along the beam; securing rods to said lower beam and passing the rods through said upper beam; pouring plastic material between the forms to form a lower part of a fire wall section; then simultaneously lowering all parts of the beam and wall section; building up the form and repeating the pouring and method until the wall section is below the water line and has been built up substantially to the deck; securing rods to the upper beam; removing said forms, structure and bolts to allow the rods to support the wall; and loosely anchoring the wall to adjacent piles.
- 10 29. In combination, a pier comprising a deck and transverse bents of piles supporting the deck; a vertical masonry wall suspended from said deck transversely of the deck near one of said bents entirely out of contact with the piles and movable transversely of the pier relative to the adjacent bent if the deck is jarred transversely; said wall being spaced from the adjacent piles thereby allowing movement of the wall transversely of the pier relative to the piles when the pier is jarred laterally, thereby to avoid excessive shock and excessive disintegration and deterioration of the wall, and allowing repair, 15 replacement and posting of said adjacent piles without interference with and by the wall.
